UNITED STATES PATENT OFFICE

116,931

DESIGN FOR A SHOE

Henry Greenblatt, University City, Mo.

Application July 24, 1939, Serial No. 86,206

Term of patent 3½ years

To all whom it may concern:

Be it known that I, Henry Greenblatt, a citizen of the United States, residing in the city of University City, in the county of St. Louis and State of Missouri, have invented a new, original, and ornamental Design for a Shoe, of which the following is a specification, reference being had to the accompanying drawing, forming a part thereof.

I claim:

The ornamental design for a shoe, as shown.

HENRY GREENBLATT.
